Charles W. Heppenstall
Edward A. Lawrence,
his attorney.

UNITED STATES PATENT OFFICE.

CHARLES W. HEPPENSTALL, OF PITTSBURGH, PENNSYLVANIA.

HEATING FURNACE FOR INGOTS, BILLETS, AND THE LIKE.

Application filed April 21, 1921. Serial No. 463,213.

To all whom it may concern:

Be it known that I, CHARLES W. HEPPENSTALL, a citizen of the United States, and residing in the city of Pittsburgh, in the county of Allegheny and State of Pennsylvania, have invented or discovered the new, useful, and Improved Heating Furnace for Ingots, Billets, and the like, of which the following is a specification.

10 My invention consists of certain new and useful improvements in heating furnaces for ingots, billets, and the like, and it more particularly relates to fluid fuel, either gaseous or liquid.

15 My invention is characterized by new and improved means for preheating the air which is used in the fuel burners.

Preheating the air by means of checker-work is well known in the art; two sets of 20 checkerwork being provided, the hot gases being passed through one set to heat the same, while the air for the burners is heated by being passed through the other set. This arrangement requires careful attention, 25 for if the hot gases are left turned on for too long a period, the brickwork is soon burned out and requires rebuilding. Moreover the temperature to which the air is pre-heated is not constant or uniform, as the 30 checkerwork cools rapidly after the air is turned through it. This of course makes the operation of the furnace irregular and hard to control.

35 In my improved furnace no duplication of the air preheating means is required, nor is it necessary to have expensive valves and flues. On the contrary the preheating means, which I provide, is in constant use while the furnace is in operation, and the 40 temperature to which the air is preheated is kept uniform; thereby enabling me to obtain the best results from the furnace.

Generally speaking my improved furnace 45 comprises a heating compartment on the floor of which are placed the ingots or billets, and into which the burners project the gas or oil flames; a preheating compartment into which a portion of the hot gases or products of combustion are admitted from 50 the heating chamber, and an air chamber in the upper part of the preheating compartment and to which chamber the air is supplied to be heated, under constant pressure, and from which the air is fed to the burners.

Other novel features of construction, and 55 of arrangement of parts will appear from the following description.

In the accompanying drawings, which are, however, merely intended to illustrate a practical embodiment of the principles of 60 my invention without limiting the scope thereof to the construction shown, Fig. 1 is a vertical longitudinal section of a heating furnace embodying the principles of my invention taken along the line I—I in Fig. 3; 65 Fig. 2 is a vertical section taken along the line II—II in Fig. 1; Fig. 3 is a horizontal section taken along the irregular line III—III in Fig. 1, and Fig. 4 is a vertical section taken along the irregular line 70 IV—IV in Fig. 3.

The following is a detailed description of the drawings.

The furnace is composed of two main compartments included between the side walls 75 1. The front compartment A, in which the ingots or billets are heated, is separated from the rear compartment B by means of the wall 2. The floor 3 of the furnace preferably extends through the two compartments. 4 represents one or more arched ports below or in the wall 2 connecting the two compartments preferably at or near their bottoms. 5 is the roof of the compartment A, and 6 is the vertically sliding door which forms the front 85 closure for the heating chamber A.

C is a closed air chamber in the upper part of the compartment B. I show the same in the form of a steel tank which spans said compartment transversely, its ends resting in the side walls 1 which are built up around and above the tank. The front and rear walls of the compartment B are preferably reduced in thickness, as at 6^a to insure free passage for the hot gases up around 90 the sides of the tank C. The top closure of the compartment B, which is spaced well above the tank C, is shown in the form of a refractory tile 7; and 8 represents one or more relatively small ports for the escape of 95 the hot gases from compartment B.

9 is an air-supply pipe, connected to a blower or other source of compressed air, not shown, and leading down through the closure 7 to the top of the tank C, and 10 represents the air supply pipes leading from either end of the tank C to the air passages 100 of the fuel burners D which project into

ports 11 in the side walls of the heating compartment A. One of said burners is preferably near the front of the compartment A, while the other is near the longitudinal center of the compartment, as indicated in Fig. 3.

The escape for the major portion of the hot gases from the compartment A is through the ports 12 in the front sides of said compartment connecting with the vertical flues 13, which connect at their lower ends with the cross flue 14, which in turn connects with the stack flue 15.

It is evident that when the furnace is in operation a portion of the hot gases will pass rearwardly through the port 4 into the compartment B, rising up around the tank C and filling the crown of the compartment B, thus thoroughly and uniformly heating said tank. The escape of the hot gases from the compartment B is retarded by the limited capacity of the small ports 8. As a result the air under the proper pressure, maintained by the blower, will be supplied at a uniform temperature to the burners, and the temperature of the heating compartment A is thus kept at the proper degree.

The temperature to which the air is preheated depends upon the temperature of the hot gases entering the compartment B through the port 4, and therefore the control of the burners in turn controls the temperature of the air admitted to the burners; thus enabling the preheating of the air to be regulated by the adjustment of the burners. The control of the furnace is thus greatly simplified. Inasmuch as the preheating of the air is accomplished by means of a single, automatically operating mechanism, there is no danger of fluctuations of furnace temperature owing to the neglect of the operator, and thus the best and most uniform results are obtainable.

My improved air-preheating mechanism is 45 much less expensive to build and maintain than the checkerwork now in general use, and when repairs are necessary, the same can be made in much less time and with much less expense.

The percentage of the hot gases or products of combustion admitted from the compartment A to the compartment B may be varied. I have obtained excellent results in practice by permitting all of the hot gases 55 from the chamber A to enter the chamber B.

What I desire to claim is:—

1. In a heating furnace of the character described, the combination of a heating compartment, fluid fuel burners projecting into 60 said compartment, a second compartment communicating with said heating compartment to receive hot gases therefrom, a closed chamber supported in the upper portion of said second compartment connected to a supply of air under pressure, said second compartment being provided above said closed chamber with relatively small ports for the escape of the hot gases into the atmosphere, and pipes connecting said closed chamber 65 with said burners, for the purpose described.

2. In a heating furnace of the character described, the combination of a heating compartment, fluid fuel burners discharging into 75 said heating compartment, a second compartment communicating with the heating compartment to receive hot gases therefrom, an enclosed chamber within said second named compartment connected to a supply 80 of air under pressure, pipes connecting said closed chamber with said burners, and a choked escape for the gases from the second named compartment.

Signed at Pittsburgh, Pa., this 19th day 85 of April, 1921.

CHARLES W. HEPPENSTALL.
